UNITED STATES PATENT OFFICE

163,699

REFRESHMENT TRANSPORT UNIT

Gene Kilburg, Milwaukee, Wis., assignor to
Supurdisplay, Incorporated, Milwaukee, Wis., a
corporation of Wisconsin

Application June 29, 1949, Serial No. 3,621

Term of patent 3½ years

(Cl. D14—3)

To all whom it may concern:

Be it known that I, Gene Kilburg, a citizen of the United States of America, and residing at Milwaukee, in the county of Milwaukee and State of Wisconsin, have invented a new, original, and ornamental Design for a Refreshment Transport Unit, of which the following is a specification, reference being had to the accompanying drawing, forming a part thereof.

In the drawing—

Fig. 1 is a three quarter front perspective view of a refreshment transport unit, showing my new design, and

Fig. 2 is a rear and opposite end perspective view of my new design set forth in Fig. 1.

I claim:

The ornamental design for a refreshment transport unit, as shown.

GENE KILBURG.
